[57] **CLAIM**

The ornamental design for the opaque top scalloped bottom flexible beverage container, as shown and described.

DESCRIPTION

A portion of the disclosure of this patent document contains material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front perspective view of my design for a opaque top scalloped bottom flexible beverage container showing the characteristic feature of the design, which resides in its shape together with having an opaque upper portion and an opaque scalloped design on the lower portion on both the front and back of the container.

FIG. 2 is a top view thereof.

FIG. 3 is a bottom view thereof.

FIG. 4 is a front elevational view thereof.

FIG. 5 is a right side elevational view thereof, the left side is identical; and,

FIG. 6 is a rear elevational view thereof.
